UNITED STATES PATENT OFFICE.

CONRAD KNOTH, OF HILLSIDE, NEW JERSEY, ASSIGNOR TO HYATT BEARINGS DIVISION, GENERAL MOTORS CORPORATION, OF HARRISON, NEW JERSEY, A CORPORATION OF NEW YORK.

GRINDING-MACHINE.

1,389,311.

Specification of Letters Patent. Patented Aug. 30, 1921.

Application filed August 10, 1920. Serial No. 402,682.

To all whom it may concern:

Be it known that I, CONRAD KNOTH, a citizen of the United States, residing at 38 Mertz avenue, Hillside, county of Union and 5 State of New Jersey, have invented certain new and useful Improvements in Grinding-Machines, fully described and represented in the following specification and the accompanying drawings, forming a part of the 10 same.

This invention relates to means for grinding the interior of circular shells or sleeves such as are used in roller-bearings and other structures, to furnish a smooth and perfect 15 wearing surface.

The application of a steel sleeve to the axle or casing of a roller-bearing is used to furnish a hardened surface for the roll-seats, and such sleeves required to be ground after 20 hardening.

The object of the invention is to support the sleeve and grinder-wheel more rigidly during the grinding operation, and to permit a considerable overhang of the grinder-wheel 25 spindle so that it may extend within sleeves of considerable length during the grinding operation.

These objects are attained by the means shown in the annexed drawing, in which 30 Figure 1 is a side elevation of the grinding mechanism; Fig. 2 is a plan of the same; Fig. 3 shows the end of the bearing for the grinder-spindle; Fig. 4 is a section of the parts on line 4-4 in Fig. 7; Fig. 5 is a cross-section on line 5-5 of Fig. 7; Fig. 6 35 of a plan of the bearing and nozzle for the grinder-spindle; and Fig. 7 is a side view of the nozzle with a portion broken away to 40 detail to the operation of the grinder.

The mechanism for supporting and operating the grinder is necessarily shown in connection with a grinding machine, only that part being described herein, as is essential 45 to the operation of the grinder.

In Fig. 1 the bed A is shown carrying at the left-hand the chuck-driver head B, and at the right-hand end the grinder-carrying head C with a carriage c supporting the grinder-wheel and the driving-motor D.

The grinder-spindle is coupled to the 50 arbor D' of the motor D and provided at its end with the grinder-wheel b.

The chuck is formed of a cylindrical cup carried upon the front end of a hollow spindle E, the cup F having a detachable 55 lining G shaped to snugly receive, for grinding, a sleeve H of any size within the capacity of the chuck.

Chuck support.

The outer side of the cup is fitted to rotate in a bearing F' upon the head B, and its shaft is fitted to a bearing E' upon the head, at a suitable distance from the bearing F' to permit the application of a belt I', or 60 other driving agent, to the exterior of the cup, which is shown provided with a pulley J for such belt. Such a support for the 65 chuck wholly prevents any chattering or vibration of the sleeve or grinder, the sleeve 70 H lying wholly within the bearing F'.

The detachable lining G has a taper fit within the cup and is formed with a collar or shoulder M' in its rear end, at a suitable 75 distance from the front end of the chuck to admit the sleeve to be ground, with its front end projecting slightly from the chuck.

The sleeve H is held in the chuck during the grinding operation by a collar M fitted to a thread upon the front end of the chuck, 80 and the collars are made to clear the grinder b when moving through the sleeve.

The carriage is movable on the head c transverse to the chuck F, and carries bearings f and g for the grinder-spindle b.

Lost motion of the grinder-spindle a is prevented by the use of specially designed offset bearings fitted within a tubular nozzle d which projects from its bearing d' sufficiently to carry the grinder-wheel into the 90 entire length of the sleeve to be ground, (see dotted lines d in Figs. 1 and 2).

The offset bearings are formed of half-collars or bushings f and g with one-half f fastened by screws f' within the nozzle d 95 near each end, and the other halves g adjacent and intermediate to the first.

The halves g are held loosely by screws

g^2 , and springs e' are seated in the exterior of these halves and cause such halves to press the spindle b into the halves f .

The grinder-spindle is pressed laterally always in the same direction, when grinding (away from the surface being ground), and the halves f are arranged to sustain all of this thrust, so that none of such pressure falls upon the valves g .

- 10 Only one-half of the spindle's periphery is embraced by each half-bearing, and the spindle opposite such bearing (f or g) is entirely exposed to lubrication, which is supplied freely to the interior of the nozzle d , and is retained opposite each half-bearing by a fibrous pad h , thus supplying lubricant to the spindle's surface where the entire strain is imposed.

20 The spring pressure of the halves g against the spindle a wholly prevents any chattering of the grinder and consequent roughening of the ground surface. An oil-inlet l^2 is provided on the nozzle to lubricate the bearings of the spindle, and is closed by plug.

Coupling of spindle to motor.

30 The spindle b and motor-spindle are provided with coupling sections i and j , which are held together as long as the nozzle d is clamped in the bearing d' ; but the cap of the latter is detachable and is connected with the base of the bearing by links h^3 and cams h' connected by handle h^2 .

35 The handle is shown in plan in Fig. 6 and in end-view in Fig. 3, and when pressed down it locks the cap firmly upon the bearing and grips the nozzle d tightly.

40 The provision of the cams prevents any wear or lost motion of the nozzle in the bearing, as they press the parts closely together whenever they are closed.

45 The coupling-section j has a flange at the margin which centers the coupling parts i , and one of the parts is provided with a series of four holes d^4 into which pins upon the opposite section fit snugly. This also prevents any chattering.

50 When the cap of the bearing d' is opened, the nozzle can be slid endwise to separate the coupling-sections before the nozzle is lifted from its bearing.

55 The nozzle and the contained parts are thus rendered readily accessible for adjustment or repairs.

Feeding of grinder-wheel.

60 The nozzle-bearing d' requires feeding attachments to move the grinder-wheel laterally and longitudinally of the chuck, and the carriage c is therefore fitted movably to transverse guides C' upon a slide R , which is movable lengthwise of the bed A . The carriage c has a screw h with hand-

wheel z' to move it and press the grinder 65 against the sleeve to be ground, and the slide R has a rack x meshed with a pinion x' , which is connected to suitable feed-gearing to propel the grinder into the chuck. 70

When applying the grinder to the sleeve, the feed-gearing is operated to propel the slide R slowly back and forth upon the bed A , and its motion is reversed, like that in ordinary iron-planers, by dogs y arranged 75 to contact with a reversing-arm y' (see Fig. 1) at the two limits of the desired movement.

The feed-gearing is disconnected (as by a lever z') when the slide is to be moved by 80 hand by a wheel x^2 . A gaging device to indicate the diameter of the bore produced by the grinder is indicated in Figs. 1 and 2 by reference letters o , o' , p , p' , r , q , q' , t , t' , but form no part of the present invention. 85

In like manner, electrical means for arresting the motion of the feed-carrier when the grinder is withdrawn from the sleeve is, in Fig. 2, indicated by the reference letters u , d , d' , w and w' ; but this device forms no part of the present invention. 90

Having thus set forth the nature of the invention what is claimed herein is:

1. In a grinding machine, the combination, with a spindle, of a tubular nozzle affixed to the carriage and inclosing the said spindle, and half-bearings fitted inside the nozzle to opposite sides of the spindle in offset positions, to expose one side-surface 100 of the spindle for lubrication at each bearing. 95

2. In a grinding machine, the combination, with a spindle, of a tubular nozzle affixed to the carriage and inclosing the said spindle, half-bearings fitted inside the nozzle to opposite sides of the spindle in offset positions, to expose one side-surface of the spindle, and an oil-inlet to fill the nozzle with oil and lubricate the said surfaces. 110

3. In a grinding machine, the combination, with a spindle, of a carriage, a tubular nozzle affixed to the carriage and inclosing the said spindle, and half-bearings fitted inside the nozzle at opposite sides of the spindle, the bearings upon one side of the spindle being fixed rigidly in the nozzle and the opposed bearings being provided with springs to press them and the spindle toward the fixed bearing. 115

4. In a grinding machine, the combination, with the spindle, of a tubular nozzle inclosing the spindle and containing bearings fitted to the spindle, and a carriage provided with a clamp-bearing to hold the 125 nozzle removably in its operative position upon the carriage.

5. In a grinding machine, the combina-

tion, with a carriage, of a spindle, a nozzle inclosing the spindle and containing bearings fitted to the spindle, a clamp-bearing for holding the nozzle upon the carriage, 5 and an electric motor mounted upon the carriage with its arbor coupled detachably to the said spindle.

6. In a grinding machine, the combina-

tion, with a carriage, of a spindle, a nozzle inclosing the spindle and containing 10 bearings fitted to the spindle, and a clamp-bearing upon the carriage with hinged cap and cam to clamp the cap upon the nozzle.

In testimony whereof I have hereunto set my hand.

CONRAD KNOTH.
